[57] CLAIM

The ornamental design for a teapot, as shown and described.

DESCRIPTION

FIG. 1 is a side elevation view of the teapot showing my new design;

FIG. 2 is a top plan view of the teapot shown in FIG. 1; FIG. 3 is a front elevational view of the teapot showing my new design; and,

FIG. 4 is a rear elevational view of the teapot showing my new design.

The meshlike material shown in FIGS. 1, 3 and 4 is understood to be continuous throughout its cylindrical surface.

The bottom plan view is plain and unornamented.
